UNITED STATES PATENT OFFICE.

WILLIAM HERBERT BATES, OF BROOKLYN, NEW YORK.

BURGLAR-ALARM.

1,084,696.

Specification of Letters Patent.

Patented Apr. 28, 1914.

Application filed January 9, 1913. Serial No. 741,089.

To all whom it may concern:

Be it known that I, WILLIAM H. BATES, citizen of the United States, residing at Brooklyn, in the county of Kings and State of New York, have invented certain new and useful Improvements in Burglar-Alarms, of which the following is a specification.

This invention relates to improvements to devices for attachment to doors, windows and like structures or closures for the purpose of giving warning, when an attempt is made to surreptitiously open a door or window, by exploding a cartridge or like detonating device, and has for one of its objects to simplify and improve the construction and increase the efficiency and utility of devices of this character.

Another object of the invention is to provide a simply constructed device which may be applied without material structural change to windows and doors of various sizes and constructions.

Another object of the invention is to provide a simply constructed device which may be readily applied by any person without previous skill or knowledge, and which may be readily removed from place to place or from a window to a door, or from a window to another window without change of structure to either door or window.

With these and other objects in view the invention consists in certain novel features of construction as hereinafter shown and described and then specifically pointed out in the claims, and in the drawings illustrative of the preferred embodiment of the invention.

Figure 1 is a detached perspective view of the improved device. Fig. 2 is a view of a portion of a door casing and a portion of a door with the improved device applied, and partly in section. Fig. 3 is a section on the line 3—3 of Fig. 2. Fig. 4 is a side view of a portion of a window including portions of the upper and lower sashes with the improvement applied. Fig. 5 is a section on the line 5—5 of Fig. 4.

Corresponding and like parts are referred to in the following description and indicated in all the views of the drawings by the same reference characters.

The improved device comprises a base 10 having a cartridge receiving lug 11 near one end and with spaced guide lugs 12 spaced apart and likewise spaced from the cartridge receiving lug. Projecting from

the end of the base 10 opposite to the cartridge supporting portion 11 are spaced stop lugs 13.

The lug 11 is provided with a longitudinal bore 14 to receive a cartridge or other detonating device indicated at 15, the flanged end of the cartridge being disposed at the side of the member toward the guide lugs 12. The lug 11 is of just sufficient length to receive the shell of the cartridge, and a stop pin 16 is inserted in the base 10 and extends across the outer end of the bore to prevent the shell from being inserted into the outer end of the bore and likewise designed to prevent a loaded cartridge from being inserted in the above.

Mounted for slidable and rotative movement through the guide lugs 12 is a plunger or striker rod 17 preferably wedge-shaped at one end as shown at 18 to form a chisel-like terminal which will engage against the fulminating portion of the cartridge and thus explode the same, as hereafter explained.

The rod 17 passes between the stop lugs 13 and is extended laterally at the end opposite to the striker terminal 18, as represented at 19. A spring 20 surrounds the rod 17 and engages against a stop pin 21 extending through the rod. The spring exerts its force to move the rod 17 longitudinally to cause the wedge-shaped terminal 18 to strike the cartridge, and when the rod 17 is turned to one side the off set 19 engages one of the stop pins 13 and thus holds the rod in one position with the spring 20 compressed. The base 10 is designed to be fastened by screws or other devices 22 to the casing portion 23 of a door and close to the door a portion of which is represented at 24. When thus arranged the off set 19 will extend into the path of the door when the off set is engaged with the stop lug 13 which is next to the door, and thus hold the spring compressed and the rod out of action.

When thus arranged it will be obvious that when the door is opened the off set 19 will be turned thereby and released from the stop member 13 and thus release the spring 20 which immediately drives the terminal 18 of the rod against the cartridge and explodes the same thus giving the warning that the door has been opened.

The improved device may be applied to the meeting rail 25 of the upper sash of a window with the off set 19 extending over

the racking rail 26 of the lower sash in the same manner as the off set extends into the path of the door 24. By this means if the upper sash is lowered or the lower sash elevated the off set 19 will be turned into vertical position and thus release the rod, and cause alarm to be sounded by striking the cartridge.

The improved device is simple in construction, can be inexpensively manufactured and applied and readily adapted to windows and doors of various forms and sizes by simply slightly altering the length or form of the off set 19, as will be obvious. A wire 27 is attached to the offset 19 of the rod 7 to enable the improved device to be applied to the drawers of a sideboard, bureau, or the like.

Having thus described the invention, what I claim is:

1. A device of the class described comprising a cartridge receiver having a bore extending entirely therethrough and slightly larger than the cartridge, a stop extending transversely of the bore at its outer end and covering a portion only of the bore to permit the escape of gas and other products of the explosion and also preventing the insertion of a cartridge at the outer end of the bore and preventing the insertion of a

loaded cartridge at either end of the bore, and a striking device adapted to engage a cartridge when supported in said receiver.

2. A device of the class described comprising a cartridge receiver having a bore extending entirely therethrough and slightly larger than the cartridge, a stop member extending transversely of the bore at its outer end and of less diameter than the bore to permit the escape of gas and other products of the explosion and also preventing the insertion of a cartridge at the outer end of the bore and preventing the insertion of a loaded cartridge at either end of the bore, and a striking device adapted to engage the cartridge when supported in said receiver.

3. A device of the class described comprising a base having a cartridge receiving bore at one end and with a stop lug at the other end, a spring adapted and mounted for movement upon said base and having its outer end adapted to engage with the stop lug, and a pin extending from said base in the same longitudinal plane as the rod.

In testimony whereof I affix my signature in presence of two witnesses.

WILFRED REEDER DAWKES, Inventor
